BENCH

Farid A. Iskander, Brooklyn, N.Y., assignor to Herman
Miller, Inc., Zeeland, Mich.

Filed July 9, 1969, Ser. No. 18,126

Term of patent 14 years

Int. Cl. D6—01

U.S. Cl. D15—11

FIG. 1 is a perspective view of a bench according to the invention;

FIG. 2 is a front elevational view of the bench, the rear view being a mirror image of the front;

FIG. 3 is an elevational view of one of the two identical sides; and

FIG. 4 is a plan view of the bench.

I claim:

The ornamental design for a bench, as shown and described.
